US00D783057S

(12) **United States Design Patent** (10) Patent No.: **US D783,057 S**
(45) Date of Patent: ** Apr. 4, 2017

(54) **INSULATION BLOWING MACHINE**

(71) Applicant: **Owens Corning Intellectual Capital, LLC**, Toledo, OH (US)

(72) Inventors: **David M. Cook**, Granville, OH (US); **Brandon Robinson**, Sylvania, OH (US); **Christopher M. Relyea**, Columbus, OH (US)

(73) Assignee: **Owens Corning Intellectual Capital, LLC**, Toledo, OH (US)

(**) Term: **15 Years**

(21) Appl. No.: **29/539,660**

(22) Filed: **Sep. 16, 2015**

(51) LOC (10) Cl. **15-03**

(52) U.S. Cl. **D15/10**

(57) **CLAIM**

The ornamental design for an insulation blowing machine, as shown and described.

DESCRIPTION

FIG. 1 is a front perspective view of an insulation blowing machine according to the design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines in the figure drawings represent unclaimed environment only and forms no part of the claimed design.

1 Claim, 5 Drawing Sheets
